UNITED STATES PATENT OFFICE.

CHARLES N. CLARK, OF SOMERVILLE, MASSACHUSETTS.

DUMPING WAGON.

Application filed April 26, 1920. Serial No. 376,599.

To all whom it may concern:

Be it known that I, CHARLES N. CLARK, a citizen of the United States, residing in Somerville, in the county of Middlesex and State of Massachusetts, have invented an improvement in Dumping Wagons, of which the following description, in connection with the accompanying drawings, is a specification, like characters on the drawings representing like parts.

This invention relates to a wagon for transporting and discharging coal, gravel and like material.

The invention is herein shown as embodied in a horse drawn wagon to which it is particularly applicable. The invention has for its object to provide a wagon with which the load of coal or other material can be transported and delivered by basket with a single operator, in a minimum time and with a minimum loss of coal or the like, and without imposing on the horse extra duty as will be described.

To this end the wagon body, which may be the body of the ordinary horse drawn wagon, is normally supported upon springs, is pivotally mounted so that its front end can be elevated and is provided with an elevating mechanism which is carried by the wagon body and is normally movable therewith under the influence of said springs to permit the latter to function, and is capable of being firmly supported when it is desired to tilt the wagon body on its pivot.

The wagon body is further provided at its rear end with means for preventing loss of material, and with means for supporting a basket or like receptacle while the latter is being filled, and for elevating the filled basket into a convenient position for the operator to handle.

These and other features of this invention will be pointed out in the claims at the end of this specification.

Fig. 1 is a side elevation of a sufficient portion of a horse drawn wagon embodying this invention to enable the latter to be understood.

Fig. 2 is a like view with the wagon body tilted into its discharging position.

Figs. 3, 4 and 5, details of the mechanism for elevating the front end of the wagon body.

Figs. 6, 7, 8 and 9, details of the rear end of the wagon body to be referred to, and

Fig. 10, a detail to be referred to.

Referring to the drawings, 10 represents the body portion of a horse drawn wagon, which latter may be of any suitable or usual construction except as will be, hereinafter pointed out.

The body 10 is normally supported as herein shown by a transverse front spring 12 and by longitudinally extended rear springs 13, which springs are supported by the front and rear axles 15, 16, as common in wagons of this character. The axles 15, 16 are connected by a perch 17.

The wagon body 10 is pivotally mounted so as to be tilted into an inclined position, and in the present instance it is pivotally mounted on the rear springs 13 and has its front end detachably mounted on the front spring 12. In the present instance the rear springs 13 have their upper halves connected by a cross bar 18 to which the body 10 is connected by hinges, only one of which is shown in Figs. 1 and 2, one member 19 of which is fastened to the cross bar 18 and the other member 20 to a metal plate 21 attached to the underside of the body 10. The front end of the body 10 is engaged with the front spring 12 by a pair of clips or devices, herein shown as two angle irons 22, 23 which are secured to the body 10 and are arranged to straddle the front spring 12 and thus effectively connect the front end of the body to said spring under normal conditions of use, as represented in Fig. 1, but which are capable of being disengaged from said front spring when the front end of the wagon body is elevated to tilt the latter as shown in Fig. 2.

Provision is made for tilting the wagon body by mechanical means, and to provide a solid support for said tilting means while the wagon body is being tilted, and to provide for movement of the tilting means with the wagon body, so as not to restrict or interfere with the movement of the front and rear springs under normal conditions of use.

The lifting means is preferably made as herein shown and comprises a threaded rod or screw 25 having its lower end mounted to turn in a bearing 26, see Fig. 4, pivotally secured by a pin or bolt 27 with a base plate or block 28 having ears 29 which support the pivot pin 27. The base plate or block 28 is bodily movable vertically and is herein shown as guided in such movement by pins or rods 30, erected from a plate 31 which is secured to the underside of the perch 17,

which latter is shown in Fig. 4 as provided with an opening 32 extended through it and of sufficient size to receive the base block 28.

The upper end of the threaded rod or screw 25 is engaged with an internally screw threaded hub or nut 33, which is affixed to the wagon body 10 to move therewith and is pivotally mounted to permit the screw rod 25 to remain substantially vertical while the wagon body is being raised and inclined. The nut 33 is provided as shown in Fig. 3 with laterally extended hollow bosses 34, 35 into which are extended pivot pins 36, 37 which are supported by the forked arms 38 of a yoke shaped piece 39, fastened to a cross bar 40 on the underside of the wagon body. The pivot pins 36, 37 are secured to bars 41, 42 attached to the cross bar 40 and to a cross bar 43 parallel with it. The upper end of the screw or threaded rod 25 is normally extended onto the wagon body through a suitable opening in the floor thereof, and said opening is protected by a suitable hood 44 indicated by dotted lines in Figs. 1 and 2, which prevents escape of the coal or other material through the said opening.

The threaded rod or screw 25 is rotated from a shaft 45 by a bevel pinion 46 meshing with a bevel gear 47 mounted on the screw or threaded rod 25 to turn therewith.

The shaft 45 is represented as turned by hand and is supported in bearings 48, 49, which are supported by the bearing 26 and are respectively attached thereto by the brackets or arms 50, 51.

By reference to Figs. 1 and 2, it will be seen, that when the wagon body is in its normal condition or position and loaded with coal or similar material, the shaft 45 can be turned so as to rotate the screw 25 and cause the latter to travel up through the nut 33 a sufficient distance to raise the block or base plate 28 away from the supporting plate 31, as represented in Fig. 1. When in this position, the load is carried by the springs 12, 13 in the same manner as in the ordinary horse drawn coal wagon. When the wagon reaches the house or other place where the coal is to be delivered, the operator turns the shaft 45 in the opposite direction to lower the screw until the base block 28 has been lowered into engagement with the supporting plate 31, and on the continued turning movement of the screw rod 25, the nut 33 will travel up on the screw rod and elevate the front end of the wagon body and turn the latter into an inclined position as shown in Fig. 2. The wagon body may be secured in its inclined position or in its normal position by a device for locking the shaft 45 from rotation. The locking device is shown as a forked metal piece 55, see Figs. 4 and 5, which straddles a square portion 56 of the hub of the bevel

pinion 46 and is made of sufficient length to engage the arm 50 of the bearing member 48 for said shaft.

When the wagon body is in its inclined or discharging position, the coal may be discharged into a basket or receptacle 60 through the usual opening in the tail board, which is normally closed by a suitable slide 61, see Fig. 7, and such as now commonly used on tail boards of coal wagons. The tail board may be made as a single piece but is herein shown as composed of upper and lower members or halves 62, 63, which are connected together by suitable bars or rods 64 extended through metal eyes 65 affixed to said members, or in any other suitable manner. The lower member 63 will be provided with the opening through which the coal may run into the basket 60. The tail board has attached to it a supporting member for the basket, which supporting member, as shown in Figs. 1 and 2, consists of a platform 67 supported at its opposite sides by parallel links 68, 69, which are pivoted to said platform at their lower ends and at their upper ends to brackets or arms 70 pivotally secured to lugs or ears 200 on the tail board, and if desired also supported at their outer ends by chains or like devices 71 from metal eyes 72 affixed to the member 63 of the tail board.

Provision is made for elevating the basket when loaded, up into a position where it can be conveniently handled by the operator. To this end, the supporting member 67 is connected with a windlass carried by the tail board. The windlass referred to comprises as shown a rotatable shaft 75 supported in bearings 76 affixed to the upper member of the tail board and chains 77, or the like, fastened at one end to the shaft 75 and at their other ends to the supporting member 67. The shaft 75 is provided with a crank 78, by turning which the operator can wind up the chains 77 and lift the supporting member 67 with the loaded basket or receptacle 60 thereon, from the position shown in Fig. 2 into that shown in Fig. 6, and can retain said platform in its elevated position by engaging a pawl 80 with a ratchet wheel 81 on the shaft 75. When the basket has been elevated, it can be more conveniently handled by the operator and is in a position to be easily transferred to his back. By disengaging the pawl 80, the supporting member 67 may be lowered into its normal position shown in Fig. 2. When the supporting member 67 is raised from its lowered position into its elevated position, the inner link 69 passes by the outer link 68 and to enable this to be done said links are made as shown in Fig. 10, wherein the inner link 69 is shown as provided with a boss 83 at its lower end and the outer link 68 is provided with a boss 84 at its upper end. The

boss 84 holds the lower end of the outer link 68 away from the platform 67 and the boss 83 holds the upper end of the inner link 69 away from the bracket 70, which permits 5 the links 68, 69 to pass by each other when they are moved from the position shown in Fig. 2 to that shown in Fig. 6 and vice versa.

The brackets 70 are pivoted to the tail 10 board so as to move in a vertical plane, which is of advantage, for when the basket 60 is not on the platform 67, the windlass can be operated to bring the platform 67 near to the tail board, which is permitted by 15 pivoting the brackets 70 to the tail board as described. It will thus be seen that when not in use the basket lifting mechanism can be brought close up to the tail board out of the way, in which position it is held 20 by the pawl 80. Furthermore by attaching the brackets 70 to the tail board, the latter can be dropped down in the usual manner when desired, without interference with its movements by the lifting mechanism.

25 The tail board is pivoted to the rear end of the wagon body 10 and provision is made for preventing loss of coal and especially soft or fine coal passing out between the tail board and the bottom of the wagon. To this end, 30 the member 63 of the tail board is pivoted to the bottom of the body portion 10 by means of a hinge composed of a sheet metal member 100 extended the width of said body portion and preferably set into a recess 101 in 35 the bottom of the body portion to have its upper surface flush with the upper surface of said bottom, and a sheet metal member 102 secured to the inner face of the member 63 of the tail board.

40 The sheet metal members are provided with hollow bosses 103, 104 which receive the pintle or pivot rod 105, and said bosses are fitted substantially tight, so as to make a relatively close joint and prevent soft coal 45 or other fine contents of the wagon passing between the bottom of the body portion and the tail board when the latter is in its horizontal or open position shown in Fig. 8. The member 63 of the tail board may also 50 have attached to it curved side pieces 106 to prevent the coal dropping off from the sides of the tail board when the latter is in its horizontal position shown in Fig. 8.

55 Provision is made for relieving the rear springs from strains placed upon them, especially under the influence of the load, when the wagon body is in its horizontal position and the wheels of the wagon strike an obstruction, and also when the wagon body is 60 in its downward and rearwardly inclined discharging position.

In the present instance, one arrangement or construction is shown for accomplishing this result, which consists of a stationary up-right member 110 supported by the perch

17, and a movable member which connects the upright member 110 with the rear portion of the wagon body, and in the present instance with the cross bar 18 attached to the rear springs 13. The movable member 70 referred to, is shown as threaded rods 112, 113, adjustably connected by a turnbuckle 114, and links 115, 116, connecting said rods with the stationary member 110 and with an eye-bolt 117 attached to the cross bar 18. 75 By reference to Fig. 1, it will be seen that if the rear wheels of the wagon should strike the curbstone in backing or an obstruction in the road, movement of the wagon body in the direction of its length with relation to the rear axle, is resisted by the connection between the cross bar 18 and the upright member 110, and when the wagon body is in its inclined or discharging position shown in Fig. 2, movement of the wagon 80 body in the direction of its length under the influence of the load, is resisted in the same manner.

85 The movable connection or member acts as a lever, which is pivoted to the upright 90 110, so that the end connected with the eye-bolt 117 moves in the arc of a relatively large circle and therefore allows of but slight longitudinal movement of the wagon body when the connection or member passes from 95 above the horizontal radius to below the same and vice versa.

90 As a result excessive strains on the rear springs and on connections with the rear axle are avoided or at least reduced to a 100 minimum.

Claims.

1. In a wagon, in combination, a wagon body, springs to normally support the same, means for pivoting the wagon body to permit it to be elevated at its front end into an inclined position, and elevating mechanism carried by said wagon body and normally movable therewith under the influence of said springs to permit the latter to function 105 and capable of being firmly supported when it is desired to tilt the said body on its pivot.

110 2. In a wagon, in combination, a wagon body, front and rear springs to normally support said wagon body, means for pivoting the rear end of said body to permit the front end of the latter to be elevated, means for detachably engaging said wagon body with said front spring, and mechanical means for elevating the front end of said 115 wagon body to turn the latter on its pivot and disengage the front end thereof from said front spring, said elevating means being normally carried by said wagon body to permit said springs to function.

120 3. In a wagon, in combination, a wagon body, front and rear springs to normally support said body, means for pivotally connecting said wagon body with said rear springs, means for detachably engaging said 130

body with said front spring, mechanical means for elevating the front end of said wagon body to turn the latter on its pivot and disengage the front end thereof from 5 said front spring, said elevating means being carried by said wagon body and normally movable therewith under the influence of said springs, and means for supporting said elevating means independently of said 10 springs when said wagon body is tilted.

4. In a wagon, in combination, a wagon body, springs to normally support the same, means for pivoting the wagon body to permit it to be elevated at its front end into 15 an inclined position, elevating mechanism carried by said wagon body and normally movable therewith under the influence of said springs to permit the latter to function and capable of being firmly supported when 20 it is desired to tilt the said body on its pivot, said elevating mechanism comprising a threaded rod, means for rotating it, a nut engaged with said threaded rod, and means carried by said wagon body for pivotally 25 supporting said nut to enable the threaded rod to be retained in a substantially vertical position while said wagon body is being tilted.

5. In a wagon, in combination, front and 30 rear axles, a perch connecting said axles, springs supported by said axles, a wagon body normally supported by said springs, means for pivotally connecting the wagon

body with the springs supported by the rear axle, means for detachably connecting the 35 wagon body with a spring supported by the front axle, and a lifting mechanism for elevating the front end of the wagon body, said lifting mechanism being normally carried by said wagon body and capable of cooperating 40 with said perch to be firmly supported by the latter when said wagon body is elevated and unsupported by said front spring.

6. In a wagon, in combination, front and 45 rear axles, a perch connecting said axles, springs supported by said axles, a wagon body normally supported by said springs, means for pivotally connecting the wagon body with the springs supported by the 50 rear axle, means for detachably connecting the wagon body with a spring supported by the front axle, a lifting mechanism for elevating the front end of the wagon body, said lifting mechanism comprising a member 55 attached to the wagon body, and a cooperating member movable toward and from said perch and cooperating with the latter to be supported thereby when said wagon body is elevated and to be unsupported 60 thereby when said wagon body is sustained by said front spring.

In testimony whereof, I have signed my name to this specification.

CHARLES N. CLARK.
